UNITED STATES PATENT OFFICE

155,634

DESIGN FOR A VENDING MACHINE CABINET

Eldridge H. Smiley, Rosemead, and Frederick K. Storm, Jr., Los Angeles, Calif., assignors, by mesne assignments, to Kold-Krisp Apple Service, a corporation of California

Application August 11, 1947, Serial No. 140,820

Term of patent 14 years

(Cl. D52—3)

To all whom it may concern:

Be it known that we, Eldridge H. Smiley and Frederick K. Storm, Jr., citizens of the United States, residing at Rosemead and Los Angeles, respectively, county of Los Angeles, and State of California, have jointly invented a new, original, and ornamental Design for a Vending Machine Cabinet, of which the following is a specification, reference being had to the accompanying drawing, forming part thereof.

The figure is a front, three-quarter, perspective view of a vending machine cabinet showing our new design. The side of the cabinet not shown is identical in appearance to the side shown, and the top is substantially plain.

We claim:

The ornamental design for a vending machine cabinet, substantially as shown and described.

ELDRIDGE H. SMILEY.

FREDERICK K. STORM, JR.
